Patented Sept. 30, 1975

236,980

HOUSING FOR FLUID SYSTEM CONTROL OR MODIFYING DEVICE

Francis J. Callahan, Jr., Chagrin Falls, and Bernard J. Gallagher, Mentor, Ohio, and Ulrich H. Koch and Stephen Matousek, Moraga, Calif., assignors to Whitey Research Tool Co.

Filed Mar. 22, 1973, Ser. No. 343,844

Term of patent 14 years

Int. Cl. D23—01

U.S. Cl. D23—38

FIG. 1

FIG. 2

FIG. 3

FIG. 5

FIG. 1 is a perspective view taken from the top, front and one end of a housing for fluid system control or modifying device showing our new design;

FIG. 2 is a perspective view taken from the top, rear and end shown in FIG. 1;

FIG. 3 is a top plan view thereof;

FIG. 4 is a bottom plan view thereof; and

FIG. 5 is an elevational view taken from the end opposite that shown in FIG. 1.

We claim:

The ornamental design for a housing for fluid system control or modifying device, as shown.
